RECOIL-OPERATED FIREARM

Thomas Frederick Sanders, Slough, England, assignor to Sanders Small Arms Limited, London, England

Application November 2, 1937, Serial No. 172,433
In Great Britain December 5, 1936

5 Claims. (Cl. 89—3)

The invention relates to recoil-operated firearms and is more particularly directed to arrangements for unlocking the breech bolt after a shot has been fired and retaining the locking mechanism in the open position until the bolt has returned to the locking position ready for the firing of a fresh cartridge.

The arrangement used according to the present invention avoids unnecessary friction between the bolt and the locking member in this simple type of mechanism and thus provides a re-loading mechanism suitable for sub-machine guns and other quick firing weapons as well as pistols, rifles and light ordnance.

15 According to the invention a recoil-operated gun mounted on a support to recoil longitudinally thereon against resilient means comprises in combination a locking member movable parallel to itself and adapted in one position to hold the breech bolt in place for the firing of a cartridge and in another position to release the bolt and allow it to carry out the usual re-loading movements, guiding surfaces or the like between the locking member and the recoiling parts so arranged that in operation the only movement of the locking member in relation to the recoiling parts is substantially perpendicular to the barrel, oblique guiding surfaces or the like between the locking member and the support so arranged that 20 in operation the only movement of the locking member in relation to the support is in the direction of the said oblique guiding surfaces or the like, a detent normally holding the breech casing in the recoiled position, and means actuated by 25 the bolt for releasing the detent as the bolt returns to the firing position.

It has already been proposed to actuate a locking member by a combination of oblique and perpendicular guiding surfaces, but the only arrangements of this kind providing a small longitudinal excursion of the locking member depended solely on the locking member itself for the retention of the breech casing in the recoiled position until the bolt had returned to the firing position.

45 It has also been proposed to provide a recoil-operated gun with a detent for holding the breech casing back until the return of the breech bolt to the closed position in conjunction with a breech bolt locking member not guided by oblique and perpendicular surfaces in the manner aforesaid but moving transversely in relation to the barrel and breech bolt to unlock the bolt and thereafter longitudinally with the bolt along the support.

55 The accompanying drawing serves to illustrate

diagrammatically the application of the invention to a sub-machine gun. To render the representation clearer certain parts having no relation to the invention have been omitted, such as the cartridge feed, which is effected in an oblique upward direction, and the firing mechanism.

In the figures:

Figure 1 is a side elevation of the assembly in the firing position taken in section partly on the centre line and partly near the right hand side 10 of the gun,

Figure 2 is a corresponding view immediately after firing a shot,

Figure 3 is an elevation and Figure 4 an end elevation of a part of the stand,

Figure 5 is a plan of the breech casing,

Figure 6 is an elevation of the breech bolt partly in section,

Figure 7 is a plan of the locking piece,

Figures 8 and 9 are elevation and end elevation respectively of the same, and

Figure 10 is a perspective view of the detent mechanism.

Referring to the figures, the breech casing 1 is mounted on the stand 2 by means of grooves 3 25 so as to be free to slide in a longitudinal direction. The barrel is partly shown at 25 in Figures 1 and 2. A spring 4 tends to keep the parts in the position of Figure 1 or to return them to it after recoil.

The stand 2 is provided with two upright walls 5 projecting into the breech casing 1 to cooperate in the locking arrangements as will be shown later. The breech bolt 6 slides back between these walls when unlocked to permit a spent cartridge 30 to be ejected and a new one to be inserted into the barrel by the usual well known mechanisms. The residual gas causes the rearward movement of the bolt 6. Due to this movement the recuperator spring 7 is compressed and then returns the bolt 40 to the firing position with a new cartridge in place. In Figure 2 the bolt is unlocked and has just started its rearward movement.

The bolt, shown separately in Figure 6 has a step 8 facing rearwards by which it is locked in 45 the firing position. The front face 10 of a locking piece 9, shown separately in Figures 7, 8 and 9, abuts against the step 8 to lock the bolt in the firing position. The construction of the parts by means of which the locking piece 9 releases the bolt 6 at the appropriate time will now be described.

The locking piece 9 may be considered as having an elongated body 11 and four legs 12 projecting obliquely forwards and downwards. Sub- 55

stantially vertical shoulders 13 at the upper ends of the legs 12 face rearwards and abut against corresponding forward faces 14 of the breech casing. The locking piece 9 is thus capable of bodily, substantially vertical movement only in relation to the breech casing, and when it rises high enough the front face 10 clears the step 8 on the breech bolt 6, allowing the latter to recede and carry out the usual reloading movements. This 10 position is clearly shown in Figure 2 where the body of the locking piece, being in section, appears as a hatched rectangle.

The locking piece is also guided in relation to the stand and the direction of guiding is obliquely rearwards and upwards on recoil. For 15 this purpose the four legs 12 fit accurately in oblique slots 15 cut in the walls 5 on the top of the stand. The vertical position of the locking piece 9 is thus always determined by the relative horizontal positions of the breech casing and stand, being brought to the unlocking position at the 20 end of the recoiling movement of the casing.

When the breech casing 1 has recoiled, a detent 16 pivoted at 17 on the stand 2 is urged by 25 a spring 18 into a notch 19 cut in the lower right hand edge of the breech casing. The breech casing and associated recoiling parts are thus held in the recoiled position by means entirely apart from the breech bolt 6 and locking member 9.

To release the recoiling parts after the reloading movements have been accomplished by the bolt 6 a bell crank lever 20 is pivoted at 21 on the stand 2. This lever has one arm 22 approximately horizontal at the right hand side of the gun to bear on the under side of a tail of the detent 16 projecting forwards. The other arm 23 is roughly vertical and is on the centre line of the gun to engage a groove 24 on the under 40 side of the bolt 6. As the bolt reaches its firing position the end of the groove 24 catches the arm 23, so that the arm 22 is raised and tips the detent 16 out of the notch 19. The spring 4 then returns the recoiling parts to their normal 45 firing position, bringing the locking piece 9 back to the locking position ready for the next shot.

The action of the gun will now be recapitulated. On the firing of a shot the barrel and the breech casing 1 recoil against the spring buffer 4. During 50 this movement the locking piece 9 rises vertically in relation to the breech casing as its legs 12 slide in the oblique slots 15 of the stand. When the front face 10 of the locking piece has risen high enough to clear the step 8 on the breech bolt 6 the latter recedes and carries out the reloading movements in the usual way. Meanwhile the detent 16 holds the breech casing 55 in the recoiled position by clicking into the notch 19.

60 It is only when the bolt 6 has returned to its forward position that it trips the detent 16 by means of the lever 20. The spring 4 then restores the breech casing and barrel to the firing position, and this relative movement causes the descent of the locking piece 9 in just the same way as the recoiling movement caused it to rise. The bolt is then locked and the gun is ready to fire another shot.

Obviously the various parts will be so dimensioned in relation to the ammunition to be used 70 that the bolt is not unlocked until the bullet has had time to reach a predetermined position in its flight.

What I claim is:—

75 1. A recoil-operated gun comprising in com-

bination a support, resilient means, a breech casing and barrel mounted on the support to recoil longitudinally against the resilient means, a breech bolt in the casing arranged to travel rearwards after firing and then forwards to re-load the gun, a locking member movable bodily into and out of a position in which it locks the bolt in the firing position, a guiding surface fast with the breech casing substantially perpendicular to the barrel, a cooperating guiding surface on the 10 locking member in constant engagement therewith, an oblique guiding surface on the support, a cooperating oblique guiding surface on the locking member in constant engagement therewith, a 15 detent biased to hold the breech casing in the recoiled position, and means actuated by the bolt for releasing the detent as the bolt returns to the firing position.

2. A recoil-operated gun comprising in combination a support, resilient means, a breech casing and barrel mounted on the support to recoil longitudinally against the resilient means, a breech bolt in the casing arranged to travel rearwards after firing and then forwards to re-load the gun, a locking member movable bodily 20 and having front and rear abutment surfaces substantially perpendicular to the barrel, a rearward facing surface on the bolt to engage the front abutment surface on the locking member in one position thereof and to clear it in the other position, a forward facing surface on the breech casing in constant engagement with the rear abutment surface on the locking member, an oblique guiding surface on the support, a 25 cooperating oblique guiding surface on the locking member in constant engagement therewith, a detent biased to hold the breech casing in the recoiled position, and means actuated by the bolt for releasing the detent as the bolt returns to the firing position.

3. A recoil-operated gun comprising in combination a support, resilient means, a breech casing and barrel mounted on the support to recoil longitudinally against the resilient means, a breech bolt in the casing arranged to travel rearwards after firing and then forwards to re-load the gun, a locking member movable bodily and comprising a longitudinal body with oblique legs projecting therefrom, front and rear abutment surfaces on the body of the locking member substantially perpendicular to the barrel, a rearward facing surface formed as a step on the bolt to engage the front abutment surface on the locking member in one position thereof and to clear it in the other position, at least one 40 forward facing surface on the breech casing in constant engagement with a rear abutment surface on the locking member, two upright walls on the support one on each side of the path of the breech bolt, the walls having oblique slots 45 to accommodate and guide the legs of the locking member, a detent biased to hold the breech casing in the recoiled position, and means actuated by the bolt for releasing the detent as the bolt returns to the firing position.

4. A recoil-operated gun comprising in combination a support, resilient means, a breech casing and barrel mounted on the support to recoil longitudinally against the resilient means, a breech bolt in the casing arranged to travel rearwards after firing and then forwards to re-load the gun, a locking member movable bodily into and out of a position in which it locks the bolt in the firing position, a guiding surface fast with the breech casing substantially perpendicular to 75

the barrel, a cooperating guiding surface on the locking member in constant engagement therewith, an oblique guiding surface on the support, a cooperating oblique guiding surface on the locking member in constant engagement therewith, a spring-biased detent pivoted on the support and located to enter a notch in the under side of the breech casing when the latter is in the recoiled position, a tail on the detent, a bell crank lever pivoted on the support and having one arm projecting rearwards under the tail of the detent, the other arm projecting upwards, and a forward facing surface on the under side of the bolt located to engage the upward arm 10 of the bell crank lever when the bolt has nearly returned to the firing position.

5. A recoil-operated gun comprising in combination a support, resilient means, a breech casing and barrel mounted on the support to recoil longitudinally against the resilient means, the breech casing having a notch on its under side, a breech bolt in the casing arranged to travel rearwards after firing and then forwards to reload the gun, a rearward facing abutment surface formed as a step on the top of the bolt, a forward facing abutment surface formed as the end of a groove on the under side of the bolt, a locking member movable bodily and comprising

a longitudinal body with four oblique legs projecting downwards and forwards therefrom, a front abutment surface on the body of the locking member located to engage the rearward step on the bolt in one position of the locking member and to clear it in the other, rearward facing abutment surfaces projecting from the body of the locking member at the tops of the legs, forward facing abutment surfaces on the breech casing in constant engagement with the last 10 named abutment surfaces, two upright walls on the support one on each side of the path of the breech bolt, each wall having two oblique slots to accommodate and guide two legs of the locking member, a spring biased detent pivoted on 15 the support and located to enter the notch in the under side of the breech casing when the latter is in the recoiled position, a tail on the detent, a bell crank lever pivoted on the support and having one arm projecting rearwards under 20 the tail of the detent, the other arm projecting upwards to engage the forward facing abutment surface on the under side of the bolt and located to enter into the said engagement when the bolt has nearly completed its forward travel to the 25 firing position.
